UNITED STATES PATENT OFFICE.

GEORGE ORVIL HODGE, OF BRISTOL, CONNECTICUT.

MACHINE FOR FORMING BALLS.

Application filed February 24, 1925. Serial No. 11,171.

This invention relates to a machine for forming balls and among the objects of the invention are the provision of a machine of this character which is simple in construction and effective in action.

While the invention is capable within the limits of the claims of wide modification I have, nevertheless, shown in the drawing accompanying and forming part of the present specification an advantageous form of embodiment of the invention which, to enable those skilled in the art to practice the same, will be set forth fully in the following description. I am not restricted to such description and drawings. I may depart therefrom, as practically stated, in a number of particulars within the scope of the invention defined by the claims following such description.

20 Referring to the drawings:

Fig. 1 is a top plan view of the device showing one of the rolls, or the adjustable one, tipped upwardly and the adjacent roll or the one on the left tipped downwardly.

25 Fig. 2 is an end elevation as seen from below in Fig. 1.

Fig. 3 is a side view of the machine.

Fig. 4 is an enlarged view of a ball track and is the one above the work.

30 Fig. 5 is a front elevation of the upper ball track.

Fig. 6 is a front elevation of the roller ball track.

Fig. 7 is a detail view of the work showing 35 its progressive action under certain conditions.

Fig. 8 is a like view showing other conditions.

Fig. 9 is a side elevation of the two rolls 40 in the angular relation.

Fig. 10 is an elevation of driving mechanism.

Like characters refer to like parts throughout the several views.

45 The device shown embodies in its make-up two cylinders or rolls, as 2 and 3, attached to the shafts 4 and 5 which, as shown, are in parallelism. The shafts 4 and 5 have at their front ends ball bearings, as 6 and 7 respectively, between which the stock is fed, as represented in said Fig. 1. One shaft, as 5, is adjustable toward or from its companion shaft to conform to the size of ball being rolled and also to maintain the proper angular adjustment of the rolls 2 and 3.

The shafts 4 and 5 are connected at their back ends by universal joints, as 8 and 9, with driving mechanism as will hereinafter appear and as represented in said Fig. 1. The rear members of each of the universal joints 8 and 9 are furnished with rearwardly extending shafts, as 10 and 11, connected in turn by universal joints, as 12 and 13 respectively with the driving mechanism. The driving mechanism, as shown, involves two pinions, as 14 and 15, shown in Fig. 10 and with intermediate spur gear, as 16, as shown also in Fig. 1, but represented best in Fig. 10. By the construction described both shafts and their adjacents are driven in the same direction and at the same speed which is an important consideration.

The rolling rolls 2 and 3 have in their periphery spherical grooves, as 17 and 18, and in which the stock to the roll is fed. As 75

shown, the rolls 2 and 3 have three complete threads, but this is not essential, or at least is not vital except in accordance with the diameter of the ball the number of whorls may be increased. Referring to the diameter or size of the roll 2 or 3 one of them is laterally adjustable and in this case the roller 3 is laterally adjustable. In Fig. 2 the

housing 19, which sustains the roller 3 and its component parts, is connected with the 80 companion housing 20 by bolts as 21, the threaded ends of which receive nuts, as 22,

by turning to the left or off the bearing 19 can be adjusted to the right in Fig. 2. By 85 running the nuts to the right the opposite effect can be obtained during which time the housing 19 slides on the upper surface of the stationary foot-piece 23, as best shown in Fig. 2. In Fig. 1 the shafts 4 and 5 have

adjusting nuts, as 24 and 25 and 26 and 27 90 respectively, the nuts 24 and 25 engaging side faces of the cylinder 3 while the nuts 26 and 27 receive between them the complementary cylinder 2, as best shown in Fig. 1. By the arrangement described, the cylinders 100

2 and 3 may be adjusted longitudinally of their supporting shafts, as 4 and 5 respectively and when so adjusted longitudinally and, if necessary, laterally the nuts just described will be set to maintain the adjustment so that the grooves in the rolls 2 and 3 will laterally register.

Each track which is assumed to contain a full supply of balls is shown in said Fig. 4. The stock is generally fed in a hot condi- 110

tion. As the balls feed they are subjected at the bottom of their progress by some cooling agent, such as a stream of water or oil playing upon them. The lower portion of 5 the balls, in their travel through the race, might pass through a vat containing water or other cooling agent as the balls travel as will later appear. In said Fig. 4 and in Figs. 5 and 6, I have represented the progress 10 taken by the balls. In said Fig. 5 the numeral 28 denotes the ball track shown in said Fig. 4. The balls are introduced in the mouth 29 and travel down it and then enter the space 30, Fig. 4. As each ball advances 15 the ball or balls in front are caused to travel in the direction of the arrow in said Fig. 4. Each ball in leaving the portion 30 enters the tube, as 31, which is connected at its ends by a nut 32 which acts against the flange 33 20 on an end of the tube, the nut effecting in and out movement of the tube 31 for adjustment. It will be understood that in the opening 34 a cylinder, as 2 or 3, is positioned and it feeds the balls to the right in said 25 Fig. 4 so that the power of the cylinders is effected to keep the balls constantly advancing which is the same speed as that of the lead of the grooves of the rolls. In said Fig. 6 is shown a construction adapted to the 30 lower roll and this structure is very much similar to that of Fig. 5 except that the corresponding parts which will bear prime marks. In Fig. 7 is shown a blank which is 35 different from Fig. 8 and it would be well to explain the reason for this difference. In Fig. 8 the grooves or continuous groove in each cylinder is cut parallel to the center line of the cylinder whereas in the construction shown in Fig. 7 is cut parallel to the 40 surface of the cylinder and it will be understood that the rolls 2 and 3 are a trifle conical in shape. I should call attention to the fact that the point of intersection of the final part or whorl of each pair of grooves 45 of the cylinders 2 and 3 are coincident, as shown by the center lines of the shaft in Fig. 9.

It is quite proper to observe that the diameter of each ball must be greater than the 50 work. I also wish to observe that the grooves in the rolls may be made parallel for different sized balls with the tilting angle constant by using rolls and determined diameter to thus provide for lateral adjustment.

What I claim is:

1. A ball forming machine comprising a pair of spirally grooved rolls, means for rotatively driving said rolls, balls serving as 60 means for guiding the work, and ball track and casing structures serving as means for operatively housing said balls.

2. A ball forming machine comprising similarly spirally grooved rolls, having complementary parts and relatively tilted with

respect to each other whereby the companion grooves will approach parallelism, ball tracks and ball cases containing balls and positioned between the rolls and propellable forwardly by the power of the rolls to guide 70 the work being formed.

3. A ball forming machine comprising a plurality of similarly spirally grooved rolls having complementary parts and tilted with respect to each other whereby the companion grooves will approach parallelism and whereby the angle of intersection passed through the centers of the last groove, ball tracks, and ball cases filled with balls and positioned between the rolls to guide the 80 work being formed.

4. A ball forming machine comprising duplicate spirally grooved rolls having complementary parts and relatively tilted with respect to each other, means for relatively laterally adjusting the rolls, means for relatively longitudinally adjusting one of the rolls, ball tracks and ball cases containing balls and positioned between the rolls to guide the work being formed.

5. A ball forming machine comprising spirally grooved similar rolls having complementary portions, means for relatively laterally adjusting one of the rolls, means for relatively longitudinally adjusting one of 95 the rolls, ball tracks, ball cases to receive balls and means to adjust the length of the ball cases and positioned between the rolls to guide the work being formed.

6. A ball forming machine comprising a plurality of rolls and supporting shafts therefor, means for preventing longitudinal movement of the shafts, ball tracks and ball cases to contain balls and positioned between the rolls to guide the work being 100 formed.

7. A ball forming machine comprising complementary rolls of predetermined diameter having a definite number of spiral grooves with complementary portions, duplicate mechanism for driving the rolls, means for longitudinally adjusting one of the rolls and tilted with respect to each other at a fixed angle whereby the companion grooves will approach parallelism, ball tracks and ball cases positioned between the rolls to 110 guide the work.

8. A ball forming machine comprising a plurality of spirally grooved rolls having complementary portions, ball tracks and ball cases filled with balls of greater diameter than those to be produced and positioned between the rolls to guide the work being formed and to sustain the balls when no work is passed through the machine.

9. A ball forming machine comprising two spirally grooved rolls having complementary parts, the latter part of the companion whorls being under pressure contact to sever the finished ball from the work be-

ing formed and a pair of oppositely disposed sets of guide balls serving as means to guide the work through the rolls.

10. A ball forming machine comprising complementary spirally grooved rolls, duplicate mechanism for driving the rolls, ball tracks and ball cases containing balls positioned between the rolls to guide the work to be formed.

11. A ball forming machine comprising a pair of spirally grooved rolls, grooves semi-circular shaped having a portion of the guide balls for guiding the work, and grooves relieved at the edges to conform to the shape of said guide balls and to sustain the balls when work is not being formed.

In testimony whereof I affix my signature.
GEORGE ORVIL HODGE.
